FLUID GOVERNOR

James G. Ramsey, Bucklin, Kans.

Application May 12, 1941, Serial No. 393,142

2 Claims. (Cl. 137—140)

This invention relates to fluid governors for controlling the maximum speed of motor vehicles and has for an object to provide a fluid governor having a hinged valve controlling the outlet of a by-pass from the pressure chamber connected to an adjustable operating lever through the medium of a tension device which can be adapted to confine the valve to a predetermined open position to control the speed of the vehicle.

A further object is to provide a fluid governor having ventilating means to compensate for expansion and contraction of the fluid due to temperature changes.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification—

Figure 1 is a plan view of a fluid governor constructed in accordance with the invention.

Figure 2 is a longitudinal sectional view of the governor taken on the line 2—2 of Figure 1.

Figure 3 is a cross sectional view of the governor taken on the line 3—3 of Figure 2.

Figure 4 is a cross sectional view of the governor taken on the line 4—4 of Figure 2.

Referring now to the drawing in which like characters of reference designate similar parts in the various views, 10 designates a casing having a filling spout 11 closed by a flanged cap 12 which is threaded onto the spout and is provided with a ventilating opening 13.

A partition 14 divides the casing into a pressure chamber 15 and a fluid reservoir 16. The partition is provided with a fluid inlet opening 17, establishing communication between the reservoir and the pressure chamber, and the partition is also provided with a by-pass opening 18 through which fluid escapes from the pressure chamber into the fluid reservoir.

The flow of fluid through the by-pass 18 is regulated by a plate valve 20, best shown in Figure 4, disposed in the reservoir and adapted to seat on a valve seat 21 formed on the reservoir side of the by-pass. The valve is provided at one

end laterally of the by-pass with a hinge eye 22, and a pivot shaft 23 is engaged vertically through the eye and fixed to the shaft by a pin 24, best shown in Figure 3. The lower end of the shaft is journaled in a bearing opening 25 formed in a convex semi-circular pump cylinder wall 26 which is integral with the partition. The upper end of the pivot shaft projects through the top of the casing 10 and is equipped with a short arm 27 and a long arm 28, best shown in Figure 1, having respective hubs 29 and 30, best shown in Figure 3, which are sleeved on the projecting end of the pivot shaft. The hub of the long arm is loose on the shaft, while the hub of the short arm is fixed to the shaft by a pin 31, best shown in Figure 2, to rigidly secure the short arm to the pivot shaft.

A rod 32 is pivotally connected to the outer end of the long arm, as shown at 33. The opposite end of the rod is connected to the lever 32', co-operating with the segment 33', having a series of notches 34' for holding the lever in its adjusted position and each notch representing a different speed. Pivotal movement of the long arm is transmitted to the fixed short arm by a pin 34, which is pivotally connected at one end to the long arm, as shown at 35, and is loosely engaged through an eye 36 disposed on the end of the short arm. A helical spring 37 is sleeved on the pin between the long arm and the eye 36. A knurled nut 38 is threaded engaged on the end of the pin outside of the eye 36.

Superposed pump gears 39 and 40 are fixed to respective shafts 41 and 42, which are journaled in bearings in the side walls of the casing, as best shown in Figure 3. Both gears interfit, as is usual and the lower gear rotates against a semi-circular pump cylinder wall 43. The shaft of the lower gear projects through the wall of the casing 10 and is equipped with a driving pulley 44, best shown in Figure 3, which may be connected by a belt drive to the speed responsive shaft of the vehicle such as the main drive shaft.

The casing is provided with a cylinder 45 which forms an extension of the pressure chamber 15. A piston 46 floats in the cylinder 45 and is responsive to variations of fluid pressure in the fluid chamber. A peripherally threaded disk 47 forms the outer end wall of the cylinder and is provided with a hollow nipple 48, which is threadedly engaged in one of the branches of a four-way coupling 49.

A cylinder 50 is secured to a stationary bracket 51 adjacent the carburetor feed conduit 52. The cylinder is closed at one end by a peripherally

threaded disk 53, having a hollow nipple 54 which is threaded into a branch of the four-way coupling in alignment with the nipple 48.

A piston 55 floats in the cylinder 50. A link 56 is connected to the piston and to the crank arm 57 of a governor valve 58 in series with a conventional throttle valve. A helical spring 59 is sleeved on the link and is held under compression between the piston 55 and a stop flange 8 formed on the free end of the cylinder. A rubber bellows 60 forms the end of the cylinder and is connected to the flange 8 at the wide end, the smaller end 61 of the bellows being bored to receive the link 56 of the throttle valve crank arm. The bellows permits the link to swing the crank arm under influence of the piston 55.

A cylinder 62 is threaded onto one of the branches of the four-way coupling 49. A screw plug 63 closes the last remaining branch of the coupling. The cylinder is provided with a piston 64 which floats therein and is normally urged outwardly by a helical spring 65 which is confined under tension between the piston and the branch of the four-way coupling to which the cylinder is secured. An adjusting screw 66 is engaged through the end wall 67 of the cylinder and abuts the piston 64. The four-way coupling and the lower end of the cylinder 62 below the piston therein, as well as the cylinder 45 secured to the casing 10, and the cylinder 50 secured to the bracket 51, between the pistons 46 and 55, are filled with fluid. The piston 46 responds to any increase of pressure in the pressure chamber and through the medium of the fluid between it and the piston 55 will move the piston 65 to close the throttle valve 58. Conversely, the piston 46 responds to any decrease in pressure in the pressure chamber and recedes toward the pressure chamber, to be followed in the same direction by the piston 55 under influence of the spring 59 to open the throttle valve 58 through the medium of the link 56. The cylinder 62, piston 64, spring 65 and adjusting screw 66 constitute means by which the distance between the pistons 46 and 55 may be varied.

In operation, the valve 20 is set through the medium of the hand lever 32 to regulate the maximum speed of the engine. The valve 20 is set at different distances from its seat 21, the particular distance depending upon the maximum speed at which the engine is to operate. During the operation of the engine, the spring 59 tends constantly to move the valve 58 in the direction of its fully opened position, the movement of the valve by the spring being regulated and controlled by the speed of the pump elements 39 and 40 and the distance of the valve 20 from its seat 21. During the operation of the engine, there is always sufficient pressure within the chamber 15 to prevent the opening of the valve 58 by the spring 59 beyond the required degree, the degree of pressure within the chamber depending upon the speed of the pump elements 39 and 40 and the position of the valve 20 with relation to its seat 21. When the speed of the engine increases beyond the maximum, the pressure within the chamber 15 increases sufficiently to move the valve toward its closed position, to effect a reduction in engine speed. The valve 20 may be set

to create a pressure of 5 lbs. within the chamber 15 when the crankshaft of the engine is rotating at 1500 R. P. M. Should the speed of the crankshaft increase, as for instance, to 1550 R. P. M., as would occur on down grade, the pressure would increase in the chamber 15 to approximately 7 pounds. This increased pressure would force the piston 55 in a direction to move the valve 58 in the direction of its closed position. On the reduction of the crankshaft speed to 1500 R. P. M., the pressure within the cylinder would decrease, with the result that the spring 59 would return the valve 58 to its set position. If higher engine speed limit is desired the valve 20 is moved a greater distance from its seat and if a lower engine speed limit is desired the valve 20 is moved closer to its seat.

From the above description it is thought that the construction and operation of the invention will be fully understood without further explanation.

What is claimed is:

1. A valve controlling mechanism comprising a cylinder, a piston in the cylinder connected to the valve, a spring bearing against the piston tending to move the piston in a direction to effect movement of the valve in the direction of its fully opened position, a fluid pump having a pressure chamber and a reservoir chamber and a by-pass between said chambers, the pump being adapted to be driven at various speeds and adapted to increase the pressure in the pressure chamber with increase of speed, the pressure chamber communicating with the cylinder whereby increase in the pressure in the pressure chamber acts in opposition to the spring to cause movement of the valve toward closed position, and a valve for the by-pass manually adjustable to regulate the pressure in the pressure chamber.

2. A valve controlling mechanism comprising a cylinder, a piston in the cylinder connected to the valve, a spring bearing against the piston tending to move the piston in a direction to effect movement of the valve in the direction of its fully opened position, a second cylinder communicating with said first cylinder, a piston in said second cylinder, a third cylinder angularly related to said first and second cylinders and communicating therewith at a point between the pistons, a third piston in said third cylinder, said cylinders containing a fluid between the pistons to establish an operative relation between the pistons, means for adjusting said third piston axially of its cylinder to effect a spacing of the said first and second pistons, a fluid pump having a pressure chamber and a reservoir chamber and a by-pass between said chambers, the pump being adapted to be driven at various speeds and adapted to increase the pressure in the pressure chamber with increase of speed, the pressure chamber communicating with said second cylinder whereby increase in pressure in the pressure chamber acts in opposition to the spring to cause movement of the valve toward closed position, the chambers containing a fluid contacting with said second piston, and a valve for the by-pass manually adjustable to regulate the pressure in the pressure chamber.

JAMES G. RAMSEY.
